UNITED STATES PATENT OFFICE.

EDWARD R. BRATLAND, OF CHICAGO, ILLINOIS.

WRIST BLOTTER.

1,424,981.

Specification of Letters Patent. Patented Aug. 8, 1922.

Application filed March 23, 1921. Serial No. 454,692.

To all whom it may concern:

Be it known that I, EDWARD R. BRATLAND, a citizen of the United States, residing at Chicago, in the county of Cook and State of

5 Illinois, have invented certain new and useful Improvements in Wrist Blotters, of which the following is a specification.

This invention relates to improvements in blotters, and the primary object of the invention is to provide a novel type of blotter, which is adapted to be connected to the wrist of the user so as to always be in operative position, and thereby eliminate the necessity of laying the blotter down during the turning of the papers, leaves of the book or other work.

Another object of the invention is the provision of an improved wrist blotter, embodying an extension which underlies the 20 palm of the user's hand, thereby separating the hand from the paper being written on, thus preventing the paper from becoming soiled and the matter written thereon blurred.

25 A further object of the invention is to provide a novel shield or carrier for the blotter, which constitutes the means for holding the blotter in its correct shape and position and means for holding the blotter attached to the wrist of the user, said means also constituting a shield or protector for the shirt sleeve of the user.

A still further object of the invention is 35 to provide an improved wrist blotter having advertising matter printed on one face thereof and a novel transparent shield arranged to overlie the advertising matter to form a protecting surface therefor, said transparent shield also forming the attaching 40 means for the blotter.

A still further object of the invention is to provide an improved advertising novelty of the wrist blotter type, which will be durable and efficient in use, one that will be 45 simple and easy to manufacture, and one which can be placed upon the market at a low cost.

With these and other objects in view, the invention consists in the novel construction, 50 arrangement and formation of parts, as will be hereinafter more specifically described, claimed and illustrated in the accompanying drawings, forming a part of this specification, in which drawings:

55 Figure 1 is a perspective view of the improved wrist blotter, showing the same in

operative position on the hand of the user.

Figure 2 is a top plan view of the improved wrist blotter prior to the folding thereof, and

60 Figure 3 is a detail longitudinal section through the wrist portion of the improved wrist blotter.

Referring to the drawings in detail, 65 wherein similar reference characters designate corresponding parts throughout the several views, the letter A indicates the improved blotter, which includes the blotter portion B and the transparent wrist attaching portion C. The blotter portion B may 70 be formed or cut out from a single blank of blotting paper, and as shown includes the elongated wrist attaching portion 5 and the forwardly extending palm and paper engaging portion 6. The palm engaging 75 portion 6 is gradually flared as at 7 toward its outer end and is reduced as at 8 at its point of connection with the wrist band or engaging portion 5. As clearly shown in Figure 2 of the drawing, the palm engaging 80 portion 6 is formed adjacent to one end of the wrist engaging portion 5, and this end of the wrist engaging portion 5 is provided with a reduced extension 9, which is adapted to overlie the opposite end of the wrist 85 engaging portion when the wrist blotter A is in its operative position.

The attaching portion C is formed of 90 flexible transparent material, such as celluloid and consists of an elongated wrist band 90 10. This wrist band 10 is shaped to conform to the configuration of the wrist portion 5 of the blotter B and is provided with the reduced extension 11 on one end thereof to conform to the reduced extension 9. The 95 wrist portion C adds stability to the blotter portion B and prolongs the usefulness thereof and acts as a frame or form for the blotter. The attaching portion C may be secured in any preferred manner to the blotter portion B and as shown the terminals of the wrist portion 5 of the blotter portion B is secured to the terminals of the attaching celluloid strip C by means of a snap fastener 12. The snap fastener 12 is of the usual or 100 any preferred make and includes the male portion 13 and the female portion 14. The female and male portions respectively form clamps for connecting the celluloid band to the blotter portion and also serve as means 105 for connecting the terminals or ends of the wrist portion of the device A together to 110

hold the same in its correct position on the hand of the user. While the celluloid attaching portion C has been shown permanently connected to the blotter portion B, it is to be understood that the same can be removably connected thereto so that when the blotter portion B becomes soiled or otherwise rendered useless, new pieces can be attached to the attaching portion C. It is to be also understood that other means can be substituted for the snap fastener 12 for detachably connecting the terminals of the blotter A together.

The attaching and protecting portion C also forms a smooth bearing surface for the wrist of the user, so as to permit free movement of the hand of the user over the writing paper, and if so desired, this can also form a cuff protector for the shirt sleeve of the user, so as to prevent the same from becoming worn or soiled by contacting with the desk or paper being written on.

The blotter A is particularly adapted for use as an advertising novelty and the positioning of the wrist band 5 at the portion which is adapted to be positioned at the top of the wrist can have advertising matter indicated by the numeral 15 printed thereon. This transparent flexible member C forms a protection for the printed matter.

From the foregoing description, it can be seen that an improved wrist blotter has been provided of exceptionally simple and durable construction, which will effectively hold its shape and be prevented from accidental displacement from off of the hand of the user.

Changes in details may be made without departing from the spirit or scope of this invention; but,

I claim:

1. A wrist blotter comprising a blotting portion including a body member for engag-

ing the hand of the user, a wrist portion for engaging the wrist of the user, and a celluloid protecting portion arranged to surround the wrist portion of the blotting portion. 45

2. A wrist blotter comprising a blotting member and an attaching and protecting member, the blotting portion including a 50 wrist engaging portion and a palm and paper engaging portion, the attaching and protecting member including a flexible transparent body, and means for securing the terminals of the transparent flexible body 55 and the terminals of the wrist portion of the blotting member together.

3. A wrist blotter comprising a blotting member including a longitudinally extending wrist portion, and a forwardly extending 60 palm engaging portion, the outer surface of the wrist engaging portion having advertising matter thereon, and a protecting attaching portion formed of flexible transparent material arranged to engage the wrist portion of the blotting member and to overlie the advertising matter thereon, and means for securing the terminals of the wrist engaging portion and the flexible transparent attaching and guard member together. 65 70

4. A wrist blotter comprising a blotting member including a wrist strip and a forwardly extending palm engaging portion; a flexible guard and attaching member for engaging the outer surface of the wrist strip 75 of the blotter member, leaving the palm engaging portion exposed, the terminals of the wrist strip overlapping one another when in their folded position, and a snap fastener for securing the terminals of the wrist strip together, the male and female portions of the snap fastener constituting means for securing the flexible guard and attaching member to the wrist of the blotter member. 80

EDWARD R. BRATLAND.
